UNITED STATES PATENT OFFICE.

DAMON W. BROCKWAY, OF DOVER, MAINE.

VALISE.

SPECIFICATION forming part of Letters Patent No. 337,367, dated March 9, 1886.

Application filed December 10, 1885. Serial No. 185,299. (No model.)

To all whom it may concern:

Be it known that I, DAMON W. BROCKWAY, of Dover, in the county of Piscataquis and State of Maine, have invented a new and 5 useful Improvement in Extension - Valises, of which the following, taken in connection with the accompanying drawings, is a specification.

My invention relates to extension-valises; 10 and it consists in an improved construction of the handle thereof, and the means of securing the same to the cover of the valise, all as will be readily understood by reference to the drawings, and to the claims to be hereinafter 15 given.

Of the drawings, Figure 1 represents a perspective view of an extension-valise embodying my invention, and Fig. 2 represents a central longitudinal vertical section through 20 a portion of the upper part of the cover.

In the drawings, A is the box portion of an extension-valise, made of such a size as to fit nicely within the cover portion B, to which are riveted the straps a b c, by which the portions A and B may be secured together, all in a 25 well-known manner.

The portions A and B are constructed, in a well-known manner, of the pasteboard sides and top d d, and covered with a suitable textile fabric, e, which makes a light and 30 convenient form of valise, the strength of which is sufficient for all ordinary handling. These extension-valises have usually been provided with handles of leather, the ends of which 35 are secured by thin strips of metal to metal rings, which in turn are secured, by means of other thin strips of metal, to the cover of the valise. These metallic connections by constant wear give out easily and render the 40 handle practically useless. This is very objectionable, and it is to overcome this objection that I provide the valises with the handle which is the subject of my present application, which, when once applied, will last as 45 long as any part of the valise to which it is applied.

The under side of the top of the cover B is provided with a strengthening-piece, g, of any suitable material, while immediately 50 above this piece g, upon the upper side of the cover B, is placed a stay-piece, f, of leather, metal, or any other suitable material, which, as

well as the piece g and the material of which the cover is composed, and which is interposed between said pieces f and g, is provided with two holes, some little distance apart, each corresponding in shape to the outline of the handle C when cut in cross-section. The handle C is made from two flat pieces of leather, h h, or similar material, by 55 stitching them together from a point near one end to a point near its opposite end; but said handle may be made of a single piece of leather with its ends split without altering the principles of my invention. The ends of 60 said handle C are passed through the holes in the stay-pieces f and g, and the divided portions of the ends of said handle are turned down upon the strengthening-piece g in opposite directions, and secured in that position 65 by the rivets i i, or by any other suitable fastening, which passes through the cover B and the leather or metal stay-piece f. The stay-piece 70 f not only acts as a strengthening-piece, but also prevents the fraying of the textile fabric e and the breakage of the pasteboard shell d, which would almost invariably be the case if this were dispensed with. By this 75 method a handle may be made which is readily applied, and which, when applied, is very 80 strong and enduring.

The strengthening-piece g may be dispensed with if the body of the valise is made of heavy board, as is sometimes the case, without affecting the principle of my invention.

What I claim as new, and desire to secure by Letters Patent of the United States, is—

1. In combination with the cover of an extension - valise having a covering of textile fabric, a stay-piece of stout leather, metal, or other strong material placed upon the exterior of said covering, and provided with two rectangular holes cut through the same, two corresponding holes cut through the body of the cover, and a leather handle having a portion of each end thereof separated into two parts and turned against the inside of the cover in opposite directions after having been passed through said rectangular holes, the whole being secured together by through and through 95 fastenings.

2. The combination, with the cover of a valise having a covering of textile fabric, of the stay-piece f, provided with two rectangular

holes, corresponding holes cut through the body of the cover, the strengthening-piece *g*, also provided with corresponding holes, the handle having its ends inserted through said holes, and each end separated into two parts, which parts are turned in opposite directions against the strengthening-piece *g*, and secured thereto and to the body of the valise-cover by fastenings, which pass through the stay-piece *f*, the body of the cover, the strengthening-

piece *g*, and a portion of the handle, substantially as described.

In testimony whereof I have signed my name to this specification, in the presence of two subscribing witnesses, on this 4th day of December, A. D. 1885.

DAMON W. BROCKWAY.
